UNITED STATES PATENT OFFICE.

LEVI HALLOWELL, OF CHINA, MAINE.

ICE-SCRAPER.

SPECIFICATION forming part of Letters Patent No. 311,746, dated February 3, 1885.

Application filed February 2, 1884. (No model.)

To all whom it may concern:

Be it known that I, LEVI HALLOWELL, of China, in the county of Kennebec and State of Maine, have invented a new and useful Improvement in Ice-Scrapers, which improvement is fully set forth in the following specification and accompanying drawings, in which—

Figure 1 is a view in perspective of an ice-scaper constructed according to my invention. Fig. 2 is a plan view of the inside of the right or off runner with the location of the scraper brake and stop dotted thereon. Fig. 3 is a sectional view of the runner; Fig. 4, a sectional view of the scraper at the point where the brake is attached; and Fig. 5 is a view of one end of the scraper to which the strap securing the same to the runner is fastened.

20 Like letters indicate like parts.

My ice-scaper is designed for use after the snow has been substantially cleared from the ice, and it is desirable to clear off any trodden snow or soft ice and leave the surface smooth and even.

25 In Fig. 1, *a a* are two runners connected by the cross-bars *b b*, which may be braced, as indicated at *8 8*, &c., to make the frame-work firm. To the front cross-bar the pole *6 4* is secured by means of the eyebolts *5 5*. Upon the cross-bars the springs *s s'* are placed to hold the seat *1*. The front cross-bar has also the catch *w* thereon to hold the brake *n*. Upon the spring *s'* are the teeth *2*, to hold the brake *n* when thrown back. Between the runners the scraper *m* is placed, and secured thereto by the straps *e e* and bolts *i i*. This scraper has upon it the brake *n*, secured by the bolt *o*. Upon the inside of each runner, at the lower edge thereof and touching the scraper *m*, is placed a support, *r*. *e e* are iron or steel straps, secured to the inside of each runner by the bolts *3 3*, &c.

40 In Fig. 2 the location of the several parts connected to the runner is more plainly indicated.

45 Fig. 3, showing a section of the runner, indicates the manner in which the lower edge of the same is constructed. The outer edge is beveled, as indicated at *x*, and on the inside is placed the strap *e*, about one-quarter of an inch thick, and secured to the runner by the bolts *3 3*, &c., and projecting below the wood far enough to prevent its being worn.

It is advisable to cut into the runner, so that 55 the inner surface shall be flush with the surface of the strap *e*.

The construction of the scraper *m* is indicated in Fig. 4. The plank extends between the runners, and when in use is slanted, as 60 indicated, though this is not absolutely necessary. The lower edge of this plank is beveled, so it will be in a plane with the ice. To the lower edge is secured the iron or steel cutter *t* by the screws *u*, &c. The front edge 65 of this cutter is beveled, as indicated at *v*. The straps *e e* are secured to the scraper *m* by the screws or bolts *7 7*, Fig. 5, or in any other convenient manner.

The scraper is designed, as before stated, to 70 clear the ice-field after the bulk of snow is removed, and operates as follows: The operator sits upon the seat *1* to conveniently work the brake *n*. This brake is thrown back until the cutter *t* is down as far as desired, 75 and it is then held by the teeth *2*. The runners shod with the thin plates *c c* cut through the snow down to the firm ice. This brings the cutter *t* down to the ice also. The whole is then drawn across the field and planes the 80 surface smooth and even. When it is desirable to unload, the brake *n* is thrown out of the teeth *2*, which allows the scraper *m* to turn on the straps *e e* and bolts *i i*, and it is raised from the ice and passes over the pile of loose 85 snow, &c., which has been gathered. The scraper may be held up by throwing the brake forward under the catch *w*. The lower edge of the wooden part of the scraper *m* being, as 90 stated, beveled, so as to be in a plane with the ice, the lower side of the cutter *t* is also in a plane with the ice, and there is no tendency to gouge into the same.

What I claim as my invention, and desire to 95 secure by Letters Patent of the United States, is—

In an ice-scaper, the scraper *m*, having the beveled cutter *t* and brake *n*, or its equivalent, thereon connected to the runners *a a* by the straps *e e*, all in combination, as and for the 100 purposes set forth.

In testimony whereof I hereto set my hand this 26th day of December, A. D. 1883.

LEVI HALLOWELL.
